AUBREY LEIGH PRICE, OF WAVERLY, NEW SOUTH WALES, AUSTRALIA.

COLLAR.

1,153,134.

Specification of Letters Patent.

Patented Sept. 7, 1915.

Application filed May 13, 1915. Serial No. 27,822.

To all whom it may concern:

Be it known that I, AUBREY LEIGH PRICE, a subject of the King of Great Britain and Ireland, residing at Waverly, New South 5 Wales, Australia, have invented certain new and useful Improvements in Relation to Collars, of which the following is a specification.

This invention relates to certain improvements in relation to collars, particularly to those known as "double" collars, and consists in the provision of certain means whereby the adjustment of neckties or scarfs on such collars is facilitated, which means may also 15 serve to keep the collar properly "set" when in wear.

The difficulty which is at present experienced when adjusting a "tie" on a "double" collar is mainly due to the gripping action 20 of the inner and outer folds of the collar upon the material of the tie, but is also due in part to the catching of this material upon the head of the back stud securing the collar to the shirt, and also in part to the roughness 25 of the surface of the collar over which the tie is required to move, and the object of this invention is to provide means whereby free movement of the "tie" between the folds of the collar may be obtained.

30. The two folds of a "double" collar form a more or less acute angle with each other at their point of juncture, and it is at or near this point that the intervening space is most restricted and that the binding effect 35 upon the tie, when in position between the folds, is greatest, and means taken to prevent the tie from entering the too restricted portion of the space between the folds of the collar, or to prevent the folds from closing 40 together beyond a certain predetermined degree, will prove effective in promoting to a great extent, the easy movement of the tie for adjustment purposes.

It has already been proposed that such 45 means may consist of a strip of material, of uniform thickness throughout its depth, sewn to the top of the inner fold, or of such a strip of metal temporarily fastened to the collar at that point, but, since the two folds 50 of an ordinary "double" collar, when in position, are in no case parallel but always inclined to each other so as to form an angle at their point of juncture and as the amount of curve given to an ordinary collar at the 55 point of turnover is in all cases as small as

possible in order to preserve a neat appearance—which amount of curve limits the allowable thickness of the above mentioned uniform strip—and also since the space between the inner and outer folds is not uniform but increases greatly from the back to the front of the collar when in position, the use of a necessarily thin strip of material of uniform thickness as proposed is not satisfactory in ordinary practice, for, while a 60 special form of collar may possibly be made in which the folds would when in use take parallel positions no ordinary collar is so designed or made and a thin strip attached to the top of the inner fold allows the tie 65 to override the lower edge of such strip for the greater part, if not all of its length, and so become "bound" as when no strip is used or even to a greater degree. Again, the use of a strip of uniform thickness always 70 necessitates that such strip shall be attached to the inner fold of the collar by stitching or that special provision be made both in the inner fold and on the strip to enable such to be temporarily attached to the fold. 75

Now one object of the present invention is to provide means to efficiently serve the purpose described which may be applied to any ordinary form of "double" collar and which requires no stitching nor any special formation in the collar, such as button holes or other devices, in order to retain said means in position when in use.

A further object of the invention is to provide means to prevent the fabric of the tie from catching on the head of the stud at the back of the collar when in position and such means may be combined with the means employed for the purpose previously described and may also serve to keep same 90 in position between the folds of the collar. Another object of the invention which may be combined with the means employed for either of the above mentioned purposes, is to provide a smooth surface against which 95 the tie may move during the adjustment process.

The means employed, according to the present invention, to prevent the tie from entering the too restricted portion of the space between the folds of a "double" collar consist of a distance-piece arranged to make contact with the two folds at a point some distance below the top of the folds to bridge and close the space between them, 100 105 110

formed separate from the collar and placed in position between the folds as required. Such distance-piece would preferably be of tapered section, or so made that it may assume such a section, to conform to the angular formation of the space between the folds of the collar and so designed that when pressed up into such space it is held in position by the pressure of the two folds 10 against it. If not made of tapered section, or so arranged that it may assume such a section, the distance-piece would be made of such a thickness, or with a projecting edge equivalent to such a thickness, that it 15 could not enter the too restricted space between the folds and would thus prevent the tie from entering such space since it would be placed in position above the top edge of the tie and make contact with each of the 20 converging folds of the collar. The distance piece may also be of such form that a portion thereof abuts against the turned over portion, or point of juncture, of the fold of the collar and a thicker portion 25 forms an abutment for a tie or the like, at a distance from said point of juncture. The distance piece may be provided with lugs, or a continuous flange, projecting downward from its bottom edge whereby it may 30 be secured in position by the tie, it may be serrated or cut inwardly from its outer edge to enable it to be readily bent to the circular form of the collar when in use, and it may if desired be made of stiff springy 35 material and permanently shaped to conform to the circular shape of the collar. If permanently shaped and made of springy material the distance piece may be so made that when in position it is slightly extended 40 from its normal shape and it would then serve to keep the collar properly "set" with its front edges closed together.

This distance-piece may be made of any desired length and may either extend almost 45 wholly around the collar or be placed only at the back or at other points if desired.

To prevent the fabric of the tie from catching on the stud head at the back of the collar a thin strip of material may be 50 attached to the distance-piece, or form part of it, such strip projecting downward to cover the stud hole in the collar, and therefore the stud head when the collar is in position, and preferably presenting a smooth 55 surface over which the tie may easily be drawn. The strip would preferably be of flexible material so that it may readily be lifted during the process of attaching the collar to the stud. The tie would be placed 60 over the strip which may also serve the purpose of the projecting lugs previously mentioned to keep the distance piece in position. As previously stated, the distance-piece may 65 be provided with a number of lugs or a continuous flange projecting downward

from its bottom edge and the surface of such lugs or flange may be made very smooth in order that the tie may move over it without frictional resistance. A thin strip of smooth material may be used for 70 this purpose, independently of any distance-piece and such a strip may be combined with a stud covering piece such as previously described, or a single strip may be made to serve the two purposes. 75

Referring to the drawings which illustrate by way of example three slightly modified forms of the invention each alike serviceable for the purposes described, Figure 1 is a front view of the device in accordance with the invention, separate from the collar, Fig. 2 is a section on line *a*—*b* in Fig. 1, Fig. 3 is a section on line *c*—*d* in Fig. 1, Fig. 4 is a plan view of Fig. 1, Fig. 5 is a general view of the device applied 80 to a collar, the collar being shown as cut through at the back, on the line of the back stud, which is shown in position and broken away in part to clearly show the arrangement of the device. The tie is shown in position. Fig. 6 is a front elevation of a modified form of the invention. Fig. 7 is a section on line *e*—*f* in Fig. 6. Fig. 8 is a section on line *h*—*k* in Fig. 6. Fig. 9 is a front elevation of a further modification of the 85 invention. Fig. 10 is a section on line *l*—*m* in Fig. 9.

As shown in the drawings the device, which may be termed a "tie-easer" consists of a distance-piece A combined with an 100 anti-friction strip B and with a stud-covering piece C, the whole combination being designed to overcome every difficulty previously enumerated, in connection with the adjustment of a tie to a "double" collar, 105 but obviously the distance piece A may be used alone, or in combination with either of the parts B or C. The parts B and C might also be used without the distance piece A, to overcome certain of such difficulties. 110

In the drawings the anti-friction strip B is so combined with the distance-piece A as to also efficiently serve the purpose of an attachment for the latter to the collar by means of the tie. 115

In Figs. 1 to 5 inclusive the distance piece A is shown formed in one piece with the anti-friction strip B and the stud-covering piece C and takes a substantially truncated cone formation so as to conform with the 120 shape of the space into which it fits, between the folds of the collar. The "tie-easer" is made part circular in shape so as to conform to the circular shape of the collar when in use. 125

The tie-easer may be made extended in length or shortened as desired.

The "tie-easer" may be molded so that its front ends have to be slightly opened out in order to conform to the circular shape of 130

the collar and it would then act to keep the front ends of the collar tightly closed together and the collar properly "set." This formation is shown by the dotted outline in 5 Fig. 4.

In Figs. 6, 7 and 8 the distance piece A is again formed in one piece with the anti-friction strip B and the stud-covering piece C but the piece A is formed of two parts D 10 and E, one of which, D, enters the very narrow part of the space between the folds and keeps the other projecting part E, at a certain distance below the point of juncture of the two folds of the collar thus providing 15 that such projecting piece E, though not being limited in thickness by the amount of turnover at the point of juncture, may be made to project a considerable distance beyond the general outer surface of the tie-easer 20 to make contact with the outer fold and provide an efficient "stop" against which the tie may abut. In Figs. 6, 7 and 8 the tie-easer is made straight and in order that it may readily be bent to conform to the circular 25 shape of the collar the projecting part E is perforated or cut crosswise at numerous points through its length as shown at F.

In Figs. 9 and 10 the projecting part E of the distance piece A is made solid and may 30 be formed of different material from the remainder of the tie-easer and be attached to same by stitching, cementing, or other means. It would preferably be made of rubber, felt, cord or braid, or other very flexible 35 material. In these figures (9 and 10) the anti-friction strip B is shown of a depth equal to that of the stud-covering piece C which is then formed by simply slotting the strip B at points H.

40 The tie-easer would preferably be made

of very thin sheet celluloid or other smooth material.

I claim:—

1. In a device of the character described for use with turn-down collars, comprising 45 a single fold strip of material adapted to project up into the fold of the collar and having a laterally-projecting rib spaced a distance below its upper edge adapted to serve both as a spacer for the two members 50 constituting the fold of the collar, and as an abutment to prevent the tie from slipping upward into the angle of said fold, the lower portion of said strip having a continuously 55 smooth surface on which the tie slides freely and serving to completely cover the head of the rear collar button, substantially as described.

2. A device of the character described for use with turn-down collars, comprising a 60 single fold strip of material adapted to project up into the fold of the collar and having a laterally-projecting rib spaced a distance below its upper edge adapted to serve both as a spacer for the two members 65 constituting the fold of the collar, and as an abutment to prevent the tie from slipping upward into the angle of said fold, the lower portion of said strip having a smooth surface on which the tie slides freely, and 70 said lower portion being also provided with a tab to cover the rear collar button, when the collar is in use, substantially as described.

In testimony whereof I affix my signature in presence of two witnesses.

AUBREY LEIGH PRICE.

Copies of this patent may be obtained for five cents each, by addressing the "Commissioner of Patents, Washington, D. C."

It is hereby certified that in Letters Patent No. 1,153,134, granted September 7, 1915, upon the application of Aubrey Leigh Price, of Waverly, New South Wales, Australia, for an improvement in "Collars," an error appears in the printed specification requiring correction as follows: Page 3, line 44, claim 1, strike out the word "In" and make the article "a" a capital *A*; and that the said Letters Patent should be read with this correction therein that the same may conform to the record of the case in the Patent Office.

Signed and sealed this 5th day of October, A. D., 1915.

[SEAL.]

R. F. WHITEHEAD,
Acting Commissioner of Patents.
